Primary Examiner — T. Chase Nelson*Assistant Examiner* — Kathleen M Sims(74) *Attorney, Agent, or Firm* — Banner & Witcoff, Ltd.(57) **CLAIM**

The ornamental design for a dishwasher, as shown and described.

DESCRIPTION

FIG. 1 is a perspective view of a dishwasher showing my new design;

FIG. 2 is a front view thereof;

FIG. 3 is a right side view thereof;

FIG. 4 is a left side view thereof; and,

FIG. 5 is a top view thereof.

The broken line showing of features on the bottom and rear of the dishwasher are for environmental purposes only and forms no part of the claimed design.

1 Claim, 5 Drawing Sheets**FIG. 1**

FIG. 2

FIG. 3

FIG. 4

FIG. 5
